UNITED STATES PATENT OFFICE

BENJAMIN H. FREEDMAN, OF NEW YORK, N. Y., ASSIGNOR TO HUDSON HOLDING CORPORATION, OF NEW YORK, N. Y., A CORPORATION OF DELAWARE

LIP STICK HOLDER

Application filed January 17, 1931. Serial No. 509,345.

This invention relates to an improvement in holders or containers for lip sticks, cosmetics, or other merchandise adapted to be contained in containers of the same general construction.

The object of the invention is to provide a novel form of container which affords convenience in use. The type of containers employed at the present time for holding lip sticks consist generally of two telescoping parts, one of which forms the body of the container and the other forming a separable and removable cap or cover therefor. With this standard type of lip stick container, it is a very common occurrence for the removable cap or cover to become lost. This is caused by reason of the fact that the two hands of the user of the lipstick are generally employed while applying the lip stick; one of the user's hands generally holds the lip stick and the other a mirror. The lipstick container cap is generally laid aside and consequently forgotten, and in many cases it becomes lost. Other types of lip stick containers have been made wherein the cover has been hinged or otherwise movably secured to the body of the container. These are not only expensive to manufacture but they sometimes cause the lip stick to be broken off when the user of the lip stick absent-mindedly attempts to replace the cap without retracting the lip stick material into the body of its container.

The primary object of this invention, therefore, is to provide a lipstick container with a simple form of cover that is wholly removable therefrom, and which shall be provided with means intended for engagement by one of the fingers of the hand so that it may be held by a single finger thereof, while the other fingers of the same hand may be used in holding the lip stick container and applying the stick to the lips. Through my improved construction, the container cover or cap will not become lost since

it is constantly maintained on one finger of the hand and is immediately replaceable thereby when the application of the stick to the lips has been completed.

While I have herein described my container as being particularly applicable to holding the lip stick material or other cosmetics, it will be obvious that it will be likewise applicable to containers of similar design, construction or purposes.

Reference is to be had to the accompanying drawing, forming a part hereof in which

Figure 1 is a front elevation of my improved lip stick container;

Figure 2 is a similar view, the same being taken at right angles to that disclosed in Figure 1;

Figure 3 is a sectional view of the container cap and upper portion of the container;

Figure 4 is a plan view of the cap; and

Figure 5 is a perspective view showing how the cap is maintained by the small finger of the hand and the container portion held by several of the other fingers on the same hand.

Throughout the various views of the drawing, similar reference characters designate similar parts.

In the embodiment of my invention, disclosed in the accompanying drawing, 1 indicates the body of the container. The same is preferably made of thin metal or some similar material and it is of cylindrical form. Its lower end is provided with a knurled rotatable portion 2, which forms a part of a device for projecting the lipstick material 3 out of the body of the container body 1 to permit its application to the lips. The lipstick-moving means, of which the element 2 forms a part, being no part of my invention, need not be described in detail, the same being old and well known in this art.

Adjacent its upper end, the body 1 of the container is provided with a circumferential

bead 4 which acts as a stop or abutment for the cover or cap 5 which telescopes with the body portion of the container 1, and seats upon said bead 4, as is clearly disclosed in Figures 1 to 3 inclusive. The cap 5 is a cup-shaped tubular member which fits snugly over the end of the body 1 of the container and frictionally maintains its position thereon. Said cover or cap 5 is provided on its end with a loop or ring 6 of sufficient size to permit the small finger 7 of a person's hand to be inserted thru it.

From the foregoing, the operation of my improved device will be readily understood. To remove the cap or cover 6 from the container, it is merely necessary for the user to thrust her small finger 7 through the loop or ring 6 and draw the cap off. The finger will snugly fit within the loop or ring 6, so that the cap will be frictionally held on the finger, leaving the remaining fingers of the same hand free to hold and apply the lip stick. When the application of the lipstick to the lips has been completed, the cap is merely replaced on the container and the finger 7 withdrawn from the loop or ring 6.

In the drawing, I have disclosed the loop or ring 6, formed as an integral part of the cap 5. It will be apparent that the same may be formed separate therefrom; it may be of different shape than that disclosed, and that it may be attached to the cap by soldering or by affixing it in any other way. I have also shown the ring or loop 6 as being a rigid part of the structure. It may also be hinged to the cap if preferred and raised when desired to permit the insertion of the finger. These and other changes may be made in the structure without departing from the spirit of my invention.

What I claim is:

1. A container of the character described having a removable cover and a finger-engaging part on said cover permitting said cover to be removed from the container and supported by a single finger of the user's hand.

2. A container of the character described having a removable cover provided with a loop member through which a finger of the user's hand may be inserted.

3. A lip stick container having a body portion, a removable cover telescopically fitted thereon, the outer end of said cover being formed with a loop to receive a finger of the user's hand.

4. A lip stick container having a body portion, a removable cap fitted thereon, the end of said cap being formed into an integral loop to receive a single finger of the user's hand.

5. A lip stick container having a removable cover member, said cover member having its end formed into a rigid ring-like extension adapted to be engaged by a single finger of

the hand to remove the cover member from the container and wholly support it.

6. A tubular container having a body portion, a removable cover telescopically fitted thereon, a finger-engaging portion on the cover at its end, said portion permitting said cover to be removed from the container and supported by a single finger of the user's hand.

Signed at the city, county and State of New York, this 16th day of January, 1931.

BENJAMIN H. FREEDMAN.
